NEEDLE PULLING THIMBLE

Varnall Donald Lake, Oradell, N.J.

Application June 23, 1949, Serial No. 100,869

5 Claims. (Cl. 223—101)

1

This invention relates to a device for gripping a needle to facilitate the pulling of the needle through material which offers resistance to the passage of the needle therethrough, and more particularly the invention contemplates the combination of a needle puller and thimble.

A prime object of the invention is to provide a needle puller which shall embody novel and improved means for grasping the needle so that the needle can be easily but firmly gripped and pulled through the material.

Another object is to provide a novel and improved combination of a needle puller and a thimble wherein the thimble shall have a transverse opening therethrough intermediate its ends to receive a needle and there shall be means within the thimble for firmly clamping the needle in said opening.

Further objects are to provide a needle puller of the character described including a body portion, a needle-gripping block, a needle-gripping jaw to cooperate with said block to grip a needle between them, and novel means for mounting said gripping jaw on said body portion; and thus to utilize the sidewalls of a thimble as the body portion and to form the jaw as the end of the thimble to be used for pushing a needle through material being sewed.

Other objects are to provide a needle pulling thimble which shall be simple, reliable and inexpensive in construction; and to obtain other advantages and results that will be brought out by the following description in conjunction with the accompanying drawings in which:

Figure 1 is a perspective view of a needle pulling thimble embodying the invention showing the manner of using it for pulling a needle through material;

Figure 2 is an enlarged vertical longitudinal sectional view through one form of the needle pulling thimble;

Figure 3 is a fragmentary transverse sectional view on the plane of the line 3—3 of Figure 4;

Figure 4 is a view similar to Figure 2 showing a modification of the invention;

Figure 5 is a fragmentary side elevational view of another form of the needle pulling thimble;

Figure 6 is a vertical longitudinal sectional view approximately on the plane of the line 6—6 of Figure 5;

Figure 7 is a transverse sectional view on the plane of the line 7—7 of Figure 6; and

Figure 8 is a view similar to Figure 6 showing the manner of gripping a needle with the needle puller.

Specifically describing the embodiment of the invention illustrated in Figures 2 and 3, the reference character A indicates the body of the device which is shown in the form of a thimble of the usual frusto-conical configuration having an open end surrounded by a rim 1 and a closed end 2, the sides and end having the usual indentations or serrations to facilitate engagement with the end of a needle for pushing the needle through material being sewed. The body A may be of any suitable size and shape and formed of any suitable material.

Extending transversely and preferably diagonally across the closed end portion of the body 15 is a tube B for receiving a needle C when it is desired to pull the needle through the material being sewed which is generally designated D. The inner surface of the tube B has needle gripping portions which are shown in the form of serrations or corrugations 3 at one side of the tube and a resilient blade 4 projecting into the tube at the diametrically opposite side thereof, so that when a needle is slipped into the tube, or the tube is slipped over the end of a needle as shown in Figure 1, the needle will be frictionally gripped between the corrugated surface 3 and the blade 4. When the needle is so gripped the thimble may be manipulated as a handle so as to pull the needle through the material D, the corrugated surface 3 and blade 4 preventing relative slipping of the tube B and the needle.

If desired an inverted cup-shaped finger shield 6 may be secured in the thimble inwardly of the tube B to protect the finger of the wearer of the thimble from contact with the tube as shown in Figure 4.

The corrugated surface 3 and blade 4 may be formed integrally with the tube B as shown in Figures 2 and 3, and of course other gripping elements than the corrugated surface and blade may be utilized.

A further modification of the invention is shown in Figures 5 to 8 inclusive where the needle puller is shown as comprising a tubular frusto-conical body E having aligned diametrically opposite openings 7 in its walls and a needle gripping block 8 secured within the body below said openings and formed with a needle bearing surface or groove 9 in alignment with the openings 7. Movable mounted in one end of the body to cooperate with the needle gripping block 8 is a jaw comprising a block 10 of a thickness to loosely fit within the groove 9 and which is secured centrally of its length by a stud 11 on a thumb piece 12 which also forms the needle

pushing end of the thimble. This thumb piece is shown as comprising a main portion 13 having a depending cylindrical shank 14 on its inner side extending into the open end of the body E and formed with an outturned perimetral flange 15 which underlies an inturned perimetral flange 16 on the body E. Normally the main portion 12 of the thumb piece rests on the exterior of the flange 16 of the body as shown in Figures 6 and 7 and the flange 15 is in spaced relation to the flange 16; and the jaw 10 is normally spaced from the bottom of the groove 9 a distance less than the diameter of an ordinary needle. However, when a needle is inserted through the openings 7 and into the groove 9, the jaw 10 is pushed outwardly of the body E as shown in Figure 8, this outward motion of the jaw and thumb piece being limited by engagement of the flange 15 by the flange 16.

When it is desired to pull a needle, the needle is slipped into the openings 7 as shown in Figures 1 and 8 and the body E is gripped as shown by solid lines in Figure 1. Then the thumb of the operator's hand is pressed firmly against the thumb piece 12 as shown by broken lines in Figure 1 so as to tightly clamp the needle between the jaw 10 and the block 8, whereupon by properly manipulating the body E, the needle can be pulled easily through the material D.

The block 8 may be secured in the body E in any suitable manner but is shown as secured by pins 18 passing through the walls of the body into the openings in the block.

Also the jaw 10 may be connected to the thumb piece 12 in any suitable way, but the riveted stud 11 is a convenient connection and preferably the thumb piece is rotatable relatively to the jaw 10.

Other modifications and changes in the details of construction of the needle puller will occur to those skilled in the art as within the spirit and scope of the invention.

I claim:

1. A needle puller comprising a tubular body one end of which is formed to receive a finger, said body having opposite openings in its wall to receive a needle therethrough, a needle gripping block within said body having a needle bearing surface in alignment with said openings, a jaw at the other end of said body and cooperative with said block to grip a needle between them, and a thumb piece for said jaw projecting from the second-mentioned end of the body for actuating the jaw, said thumb piece being a disk normally closing the second-mentioned end of said body.

2. A needle puller comprising a tubular body one end of which is formed to receive a finger, said body having opposite openings in its wall to receive a needle therethrough, a needle gripping block within said body, a jaw at the other end of said body and cooperative with said block to grip a needle between them, and a thumb piece for

5 said jaw projecting from the second-mentioned end of the body for actuating the jaw, said block having a groove in alignment with said openings to receive a needle, and said jaw comprising a block of a width to loosely enter said groove.

3. A needle puller comprising a tubular body one end of which is formed to receive a finger, said body having opposite openings in its wall to receive a needle therethrough, a needle gripping block within said body, a jaw at the other end of said body and cooperative with said block to grip a needle between them, and a thumb piece for said jaw projecting from the second-mentioned end of the body for actuating the jaw, said block having a groove in alignment with said openings to receive a needle, and said jaw comprising a block of a width to loosely enter said groove, said thumb piece being a disk normally closing the second-mentioned end of said body, and said jaw being rotatably connected to said thumb piece centrally thereof.

4. A needle-pulling thimble comprising a tubular frusto-conical body formed at one end to receive a finger having diametrically opposite openings to receive a needle therethrough, means within said body for gripping a needle disposed in said openings and including two relatively movable parts to grip a needle between them, and a thumb piece for one of said parts projecting from the other end of said body, said thumb piece being a disk to normally abut and close said body at the second-mentioned end.

5. A needle-pulling thimble comprising a tubular frusto-conical body formed at one end to receive a finger having diametrically opposite openings to receive a needle therethrough, means within said body for gripping a needle disposed in said openings and including two relatively movable parts to grip a needle between them, and a thumb piece for one of said parts projecting from the other end of said body, said thumb piece being a disk to normally abut and close said body at the second-mentioned end, said body having an inturned flange at said end and said thumb piece disk having a cylindrical shank extending loosely into said body and provided with an out-turned flange underlying and to abut said flange on said body for limiting movement of the thumb piece outwardly from said body.
